(57) **CLAIM**

The ornamental design for switch, as shown and described.

DESCRIPTION

FIG. 1 is a top perspective view of a first embodiment of a switch showing an upper surface with front and left side surfaces;

FIG. 2 is a bottom perspective view thereof showing a bottom surface with rear and right side surfaces;

FIG. 3 is a front view thereof, a rear view being identical to FIG. 3;

FIG. 4 is a top plan view thereof;

FIG. 5 is a bottom plan view thereof;

FIG. 6 is a left side view thereof, a right side view being identical to FIG. 6;

FIG. 7 is a top perspective view of a second embodiment of a switch showing an upper surface with front and left side surfaces;

FIG. 8 is a bottom perspective view thereof showing a bottom surface with rear and right side surfaces;

FIG. 9 is a front view thereof, a rear view being identical to FIG. 9;

FIG. 10 is a top plan view thereof;

(Continued)

FIG. 11 is a bottom plan view thereof; and,
FIG. 12 is a left side view thereof, a right side view being
identical to FIG. 12.

1 Claim, 6 Drawing Sheets
